UNITED STATES PATENT OFFICE.

JOHN BAUDER, OF CINCINNATI, OHIO.

CAN HOLDING AND SEALING DEVICE.

1,427,347.

Specification of Letters Patent. Patented Aug. 29, 1922.

Application filed September 20, 1921. Serial No. 502,984.

To all whom it may concern:

Be it known that I, JOHN BAUDER, a citizen of the United States, residing at the city of Cincinnati, in the county of Hamilton 5 and State of Ohio, have invented certain new and useful Improvements in Can Holding and Sealing Devices, of which the following is a specification.

It is well known that during the filling of 10 cans and sealing the same, in canning fruits, vegetables and the like, that the cans must be held in a temporarily permanent position, and the lids held down tightly onto the can mouth, so that, when the sealing wax or 15 other sealing material used is poured around the edge of the lid and can that it will not leak into the can; and that, after it has been poured, that the lid will remain in a permanent position, until the sealing material has 20 become set and hardened, and cooled to assume or take on a fixed form and condition, which will not change, until removed by human agency.

My device is simple, cheap and highly 25 efficient; it is made of wood, so that it is a non-conductor of heat, can be used in connection with a number of cans at a time, and possesses great utility in this class of inventions.

30 It is "knock-down" in character and can thus be shipped very readily and when the operator is through with it, it can be disconnected and put away in a small space until it is again needed.

35 It consists essentially of a base upon which the cans are set, provided with a central guide for the periphery of the cans at the point where they come in contact therewith, a central upright post or standard, provided 40 with a number of arms, which are "spring pressed" upon the lids on the cans, which they retain in proper and desired position.

Its various features and advantages will 45 readily become apparent from the following specification.

In the accompanying drawings forming a part of this specification:

Fig. 1, is a plan view, looking down upon the device,

50 Fig. 2, is a sectional view taken through the base part, the upright post and through one of the arms, the other parts being in elevation,

55 Fig. 3, is a plan view of the base parts, the post shown in section,

Fig. 4, is an isometric view of the device in elevation, and

Fig. 5, is a sectional view through one of the arms where it intercepts its companion arm, the other parts shown in elevation 60 and parts are also shown broken away.

In forming my device I provide in proper combination, a base 1; a guide elevation or platform 2 formed at its periphery of the inwardly curved or concave depressions or 65 recesses 3, in the present instance being four in number; and upright post or standard 5, which has a lower narrowed part 3¹, which snugly, yet tightly fits into a recess 3² in said platform 2, and, through which post 70 passes a central hole 6; through which hole passes a pin or bolt 7 carrying at its lower end a head 4 which fits flush up into a recess in the bottom plate 1 and at its upper end is screw threaded to receive a winged 75 nut 9; two cross-arms 8 having downwardly depending fingers 12, which rest on the can tops or lids.

The cross arms 8 are each cut away at the middle as shown in Fig. 2 at 13, one cut 80 away part fitting into the other, so the arms will be interlocked and be flush at the top and thus be even and uniform.

On and around the rod 7, between the top of post 5, at the recessed part 11 and between the arms 8, at their central meeting point, I place a coiled spring 10, the spring 85 at the top abutting against a washer 14.

It will be noticed that the rod 7 also passes through the central meeting part of the arms 8, (where they meet at 13), thus the arms are loose on the said rod 7, so that when the winged nut 9 on top of the arms 8 is turned, the arms will be forced downwardly and their fingers 12 will contact with and impinge against the lids 20 on the cans A, as shown in Fig. 1; when the pressure exerted is great enough to tightly hold said lids 20 down in position on the cans A, the sealing fluid or material can be poured or placed 90 around the groove at the can top; the cans should remain in this position, until set, then the winged nut 9 can be unscrewed and the tension or spring 10 removed and the cans taken out and another set replaced. The 105 spring pressure exerted holds the arms and their fingers tightly down upon the lids to exert pressure against said lids.

It will be seen in Fig. 1, that the periphery of the cans A, at the point where they 110

reach the concave depressions or recesses 3, fit into the same and are guided thereby and are by this means kept from shifting and are all held equi-distant from the central post 5 5, so that the same pressure will be exerted upon all the lids.

The platform 2 may be made of any other shape and configuration, as may also the arms 8 and their fingers 12.

10 It will be readily apparent that this device can be quickly set up for use and as quickly disconnected.

While I have described one form of device for carrying my invention into effect, 15 it will be readily apparent that I can change and modify the same without departing from the principle of this invention as set forth in this specification.

What I claim as new in my invention and 20 desire to secure by Letters Patent is:

1. In a device of the character described, a base, an upwardly extending hollow post attached thereto, a rod extending through said hollow post, a spring around said rod 25 at the top of the post, arms, said arms resting upon the top of said spring, the rod passing therethrough and means for exerting pressure upon the spring by forcing said arms downwardly.

30 2. In a device of the character described, a base part, a hollow post attached thereto, a headed rod passing therethrough, carrying at its upwardly extremity a winged nut for engaging the same, arms on said rod at its 35 top, a spring interposed between said arms

and said hollow post, said winged nut moving said arms downwardly or upwardly by exerting tension upon the spring or releasing the same.

3. In a device of the character described, 40 a base part, a hollow post extending upwardly therefrom, a headed rod passing therethrough, a spring carried by said rod at the top of said hollow post, cross arms passing over said rod and resting on said 45 spring, a winged nut at the top of said rod, capable of being screwed downwardly and upwardly so that said arms will move downwardly or upwardly.

4. In a device of the character described, 50 a base part, a guide platform thereon, an upwardly extending hollow post, a headed rod passing through said post and carrying a spring at its upper extremity above the post and cross arms, said cross arms resting on 55 the top of said spring, and a winged nut for moving the arms downwardly or upwardly by placing a tension upon said spring or releasing the same.

5. In a device of the character described, 60 a base provided with an upwardly extending post, means connected with said post for supporting arms, said arms being disposed at the top of said means, a spring controlled means for forcing said arms downwardly so 65 that the arms will press upon the can tops.

In testimony whereof, I affix my signature at Cincinnati, Ohio, this 13th day of September, 1921.

JOHN BAUDER.
